UNITED STATES PATENT OFFICE

WILLIAM A. FINLEY, OF BIRMINGHAM, ALABAMA

RADIATOR

Application filed September 23, 1927. Serial No. 221,537.

My invention relates to radiators for the heating plants of buildings, more particularly to radiators in which steam, hot water, or vapor is employed as a heating medium, and has for its object the provision of apparatus of the character designated which shall occupy a minimum of space and be possessed of improved heat radiating qualities.

A further object of my invention is to provide a radiator adapted for association with an air circulating system, and which shall embody heating units having a large heat radiating area relative to the volume of heating medium employed, and wherein the air in circulation is brought into intimate contact with all the heat radiating units and with a minimum resistance to air flow.

A still further object of my invention is to provide a radiator unit for a heating system employing a medium under pressure, wherein the unit is of a deformable shape when subjected to pressure and formed of such thin material as to be deformable under the pressure normally in the system, and to provide heat radiating members surrounding the unit which act as stays to prevent its deformation, whereby the pressure in the unit holds it in tight engagement with the radiating members, thereby enhancing the heat radiating qualities of the unit.

In the design of enclosed type radiators wherein a current of air is caused to flow over the heating units, as heretofore known to me, difficulties have been encountered in producing a unit having sufficient heat transfer qualities and fitting into the limited space provided for the radiator. Furthermore, in such apparatus, it is the usual practice to provide numerous fins or plates in contact with the radiator units to provide a better transfer of heat between the units and the air flowing thereover. These fins or plates have been made, in most instances, in such a form as to afford a tortuous path to the air, or else they have been so closely spaced that the unit has required a very rapid flow of air therethrough, so that, in either case, dust and lint carried in suspension in the air is drawn into the radiator and hangs to the fins or plates, reducing their efficiency.

In my improved radiator, I have reduced the above mentioned difficulties to a minimum by producing, first, an improved unit for the heating medium under pressure, which is of such shape as to provide the maximum area of direct radiating surface, for the volume of heating medium employed; second, by forming the radiator unit of the ultimate possible thinness consistent with safety, thus providing the minimum of resistance to conduction of heat through the walls of the unit; and third, by so joining the radiating fins or plates to the unit as to provide stays for the thin walled units and for the maximum transfer of heat by conduction from the unit to the plates or fins, and thence by radiation to the air flowing thereover. Furthermore, the arrangement of the fins or plates is such that there is a minimum resistance to air flow over the unit with a maximum contact with the plates. In a multiple unit radiator, the arrangement is such as to increase the edge contact of the air with the plates or fins, further increasing the rate of heat transfer.

Apparatus embodying features of my invention is illustrated in the accompanying drawings, forming a part of this application, wherein

Fig. 1 is a front view, partly in section, showing my improved radiator in position in an enclosing flue or cabinet;

Fig. 2 is an end elevation of the radiator and showing the flue or cabinet in section;

Fig. 3 is a sectional view showing my improved radiator as adapted for a forced draft flow of air over the heat transfer units; and

Fig. 4 is a plan view of the radiator shown in Figs. 1 and 2.

Referring now to the drawing for a better understanding of my invention, my improved radiator comprises a pair of spaced manifolds 10 and 11. The manifold 10 is provided with upper and lower connections 12 and 13 for a heating medium, such as steam, hot water or vapor. The manifold 11 is likewise provided with upper and lower connections 14 and 16 for the heating medium, the upper and lower connections to the manifolds 100

being provided so as to adapt the radiator of the next adjacent tube. The upward flow of air, as seen in Fig. 1 and Fig. 2, passes over the tubes, edgewise thereof, thus coming in contact with the greatest possible area of direct radiating surface and is split by the plates of the next adjacent tube, thus increasing the heat transfer efficiency of the unit above an installation which employs heat radiating fins all lying in the same vertical plane. 70

5 being provided so as to adapt the radiator of the next adjacent tube. The upward flow of air, as seen in Fig. 1 and Fig. 2, passes over the tubes, edgewise thereof, thus coming in contact with the greatest possible area of direct radiating surface and is split by the plates of the next adjacent tube, thus increasing the heat transfer efficiency of the unit above an installation which employs heat radiating fins all lying in the same vertical plane. 75

10 The manifolds 10 and 11 are encased by a flue 17 which may be built into the wall or set out into a room as is the practice in a cabinet type radiator. The flue 17 acts as a support for the radiator and for this purpose, supporting screws 18 and 20 extend through the sides of the flue and enter into holes formed in suitable lugs 21 and 22 formed on the manifolds 10 and 11 respectively. The flue 17 fits snugly against the walls of the manifolds so as to cause all 15 of the air passing through the radiator to pass over the heating units in a manner to be more particularly described hereafter.

15 As seen in Figs. 1 and 2, the flue or cabinet 20 is provided with an air inlet 23 at the bottom thereof, and an air outlet 24 at the top thereof so as to provide for a natural induced draft of air over the heating units. The lower opening 23 may be provided with a 25 damper 25 in order to regulate the amount of air flowing through the flue.

20 Joining the manifolds 10 and 11 are any desired number of radiator units 26. The units 26 are made of relatively thin material, 30 preferably copper, and are in the form of flattened tubes, thereby increasing the direct heating surface for the volume of heating medium flowing through them. The thinness of the metal, and the nature of the material forming the tubes is such that they 35 would be deformed when subjected to the ordinary pressure within the heating system were no means provided to stay them. The ends of the tubes 26 fit into suitable openings 40 in the manifolds 10 and 11, which latter are provided with inwardly turned bosses 27 surrounding the openings. On the outer side of the manifolds the openings for the tubes 45 are chamfered as at 28 so that the tubes may be brazed or welded in place in the manifold.

45 Each of the tubes 26 is surrounded by a plurality of plates 29 which are preferably made of smooth copper so as to offer a minimum of resistance to air flow and a maximum 50 heat conductivity. The plates 29 are formed solid and with holes provided therein snugly fitting over the tubes. They are uniformly spaced on the tubes 26 as by means of spacer washers 31. The plates 29 serve 55 as staying means for the tubes 26 and prevent the latter being deformed by the pressure within them. Furthermore, the pressure within the tubes forces the side walls outwardly into tight engagement with the plates 29 and thus increases the heat conducting 60 contact between the tubes and their surrounding plates.

65 Where a plurality of tubes are employed in a radiator, the plates 29 of each tube are in a staggered relation with respect to the plates

5 As may be seen more clearly in Fig. 4, a sufficient clearance is provided between the edges of the plates 29 and the walls of the flue 17 to permit the air to flow along the edges of the plates. The reason for this arrangement is that I have found that a greater rate of heat transfer occurs in apparatus of this type where the air comes in contact with the edges of the plates than where it comes in contact only with the surfaces thereof. The arrangement of staggered plates in a multiple unit radiator causes a division of the upflowing currents of air as they pass over each succeeding unit, thus bringing the air into intimate contact with more edge surface 90 of the plates than would be the case with plates all lying in the same plane. 95

100 In assembling the unit, the flattened tubes 26 are cut to the desired length and the plates 29 and washers 31 are placed thereon. If 95 desired, one or more of the plates 29 may be omitted near the end of the tube, where it is to be joined to the manifold, in order to leave room for the brazing or welding operation employed. After the tube has been joined to the manifold, a plate may be split and secured, in any well known manner, to the tube adjacent the manifold, in order to provide the desired heat radiating surface area. When the tubes and manifolds have been 105 joined together the whole is subjected to a test pressure higher than would be used in service. This pressure within the tubes, during the test, forces their flattened walls outwardly into tight engagement with their surrounding plates. The radiator is then 110 dipped in approximately 450° solder so that a metallic contact is formed between the plates and tubes and spacers 31, thus insuring a heat conductivity between the tubes and their surrounding units, of the highest efficiency. 115

120 The operation of the apparatus so far described will be apparent. When the damper 25 is opened, air is free to enter the lower end of the flue 17, the heating units 26 creating a natural induced flow of air through the flue or cabinet. The air striking the tubes 26 edgewise thereof comes in direct heat transfer relation with the greatest possible area of direct radiating surface and the plates 29 being in tight engagement with the tubes 26, both by reason of the pressure within the tubes and the soldering process used in joining them to the tubes, provide for the maximum heat conductivity between the tubes and 130

their surrounding plates. The metal from which the tubes and plates are formed, being preferably copper, affords the highest rate of heat conductivity of any known material from which it is practical to form the units. By reference to Fig. 4, it may be more clearly seen that my improved radiator offers a minimum resistance to the air flow through the radiator. The thin flattened tubes with the air flowing edgewise thereof and the spacing of the plates effects a minimum resistance to air flow with a maximum heat radiating surface.

Referring now to Fig. 3, I show a plurality of rows of my improved units 26 arranged cross-wise of a flue 36 with their flat sides horizontal as seen in the drawing. Mounted within the flue 36, as shown in the drawing, is a fan 37 driven by a motor 38 so as to create a current of air over the tubes 26 and edgewise of the tubes. This figure shows the adaptability of my improved unit for association with heating plants of large capacity, such as are employed in theater buildings and the like. With whatever type of heating plant with which my improved radiator may be employed, a better heat transfer can be obtained by causing the flow of the air to be normal to and edgewise of the tubes 26, as shown in all of the figures of the drawing, and with the plates of adjacent tubes in staggered relation with respect to each other.

From the foregoing, it will be apparent that I have devised an improved radiator which is simple of design and easy of manufacture, and which provides for a highly improved rate of heat transfer efficiency.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a radiator, spaced manifolds for a heating medium, a plurality of flattened tubes joining the manifolds, a plurality of heat radiating members threaded over each of the tubes to form stays therefor and joined to said tube by fusion of metal, the members of one tube being in staggered relation to the members of the other tube, and means for passing a current of air in series over the tubes.

2. In a radiator having an enclosing flue with a lower inlet and an upper outlet for air circulation, spaced manifolds for the heating medium within the enclosure, a plurality of flattened tubes joining the manifolds and extending crosswise of the flue, the tubes being turned edgewise with respect to the air current, and a plurality of heat radiat-

ing plates closely embracing the tubes and spaced from the walls of the flue.

3. In a radiator, having an enclosing flue with an inlet and an outlet for a current of air, a pair of spaced manifolds for a heating medium one at each side of the flue and extending longitudinally thereof, a plurality of relatively thin flattened tubes joining the manifolds, and radiating plates closely embracing the tubes and spaced from the walls of the flue, said plates being arranged in staggered relation with respect to each other on adjacent tubes.

4. In a radiator having an enclosing flue with an inlet and an outlet for a current of air, a pair of spaced manifolds for a heating medium one at each side of the flue and extending longitudinally thereof, a plurality of relatively thin flattened tubes joining the manifolds and arranged edgewise to the current of air, and a plurality of uniformly spaced radiating plates closely embracing the tubes and joined thereto by fusion of metal, the edges of said plates being spaced from the walls of the flue and being arranged in staggered relation with respect to each other on adjacent tubes.

In testimony whereof, I affix my signature.

WILLIAM A. FINLEY.
